UNITED STATES PATENT OFFICE.

ABRAHAM M. DELLINGER, OF LANCASTER, PENNSYLVANIA.

FEED MILL.

Application filed July 3, 1922. Serial No. 572,415.

To all whom it may concern:

Be it known that I, ABRAHAM M. DELLINGER, a citizen of the United States, residing at Lancaster, in the county of Lancaster and State of Pennsylvania, have invented certain new and useful Improvements in Feed Mills, of which the following is a specification.

The present invention relates to feed mills and especially to feed mills wherein grain and fodder are ground and crushed in such manner as to produce a mixed feed for cattle.

The grinding or crushing of the grain constituent and the cutting or chopping of the stover or fodder constituent, each separately from the other and subsequently mixing them has long been the practice in making mixed feeds. More recently, attempts have been made to produce a combined machine in which both constituents may be simultaneously reduced to desired size. In such machines a single hopper or compartment is used, the fodder being cut directly into this hopper and the grain fed or delivered directly into it at the same time and crushed by the crushing rolls. The grain, being heavier, passes into the crushing rolls first, by which it is crushed and fed forward to the grinding discs while the lighter fodder is last to reach the grinding discs. The result is a very uneven mixture. In such machines you can not regulate the proportions. Such regulation has been tried by means of slide plates arranged at the point where the mixture enters the grinding discs, as it leaves the hopper. Such disposition was intended to regulate the amount of grain passing to the grinding disc but, in using the slide, to reduce the amount of grain passing to the plate the machine choked or clogged and became useless, so that the old arrangement of separate machines had to be returned to. So, the great difficulties of a combined machine are unevenness of mixture and choking of the machine.

The main objects of the present invention are to provide a simple, efficient, compact and inexpensive combined grain and forage mill by which a thoroughly uniform mixture may be maintained without choking or clogging. Further objects are to provide a combined mill which, without change of any kind, may also be used either as a grain mill or as a forage mill.

In order to more clearly disclose the construction, operation and use of the invention,

reference should be had to the accompanying drawings forming part of the present application. Throughout the several figures of the drawings, like reference characters 60 designate the same parts in the different views.

In the drawings:—

Fig. 1 is a front perspective with the front walls removed; 65

Fig. 2 is a vertical cross section on line 2—2 of Fig. 1, looking in the direction of the arrows;

Fig. 3 is an enlarged detail view of the regulator slide, in closed position; and, 70

Fig. 4 is a like view in open position.

Any suitable framework 1 may be used to support the working parts of the machine. On this framework is mounted, by brackets or in any other desired manner, the body of 75 the mill, in which crushing and mixing elements operate and into which the several constituents of the final mixture are fed. The body comprises two contiguous hoppers or compartments or bins 2 and 3, respectively, separated by a dividing or partition wall 4. Hopper 3 is adapted to receive the chopped forage, such as fodder, hay, etc. To that end, its upper portion is inclosed by a hood 5. The front, preferably, is closed 80 or completed by a front plate 27 which is removably bolted or otherwise removably secured in place, to give ready access to the interior of the hopper. The rear of the hood 5, of course, has an opening for the entrance 90 of fodder or the like, as in my prior Patent 1,117,345. Within the hood 5 is journaled the cutter shaft 6 to which are secured a plurality of cutting blades or knives 7 adapted, when rotated by shaft 6, to cut or chop the 95 forage or fodder which passes down the fodder chute and into the opening in the rear of the hood into hopper 3, in the same manner in which it is fed to the shredders in my prior Patent 1,117,345. There are various 100 other ways in which the fodder may be fed to the cutting or chopping knives, of course, but the arrangement disclosed in my said patent has proven highly satisfactory.

Shaft 6, it will be seen, is extended clear 105 across to the opposite end of the machine. This is so that a pulley mounted on the outer end may be driven by a belt from the main shaft 8. At a point near the driving end, it is supported by a suitable bearing carried 110 by the wall of the grain hopper 3. The fodder chute along which the fodder is fed to

the chopper, though very practical and highly desirable is not absolutely essential to the operation of the machine. The fodder could be fed in by hand though that 5 would be highly impracticable for any real utility of the machine. So, a chute similar to that used in hay choppers, fodder shredders, etc., is secured in position to guide the fodder directly to the cutting or chopping 10 knives, as in my prior patent, above mentioned.

The hopper 3 is open at the top and adapted to receive corn or any other grain which it is intended to incorporate with the 15 fodder or other forage as a constituent of the mixed feed. The upper end or top of this hopper is left open so that the grain may be poured or dumped or fed in in any desired manner. A removable front plate 20 24 secured in place by cooperating pivoted bolt and ears 25 and 26, respectively, complete hopper 3.

Extending longitudinally through the two hoppers, just slightly above the bottom of 25 the same and projecting beyond the end walls of the hopper and, slightly, beyond the ends of the frame 1, is a main, operating, or drive shaft 8. That section of the shaft which extends through hopper 2 is provided 30 with a plurality of spirally disposed crushing teeth or projections 9 distributed longitudinally of the shaft. As the shaft is rotated, by any usual and well known means, the crushing teeth will cooperate with a concave of usual and well known construction, 35 in the bottom of the hopper, to crush between them the corn or other grain. To more effectually crush the grain, a second shaft 10 is provided, extending through the 40 hopper 2 and journaled in its end walls. It is geared to and driven by the main shaft 8. The gearing connection between the two is such that the shaft 10 is driven at a very 45 much slower speed than shaft 8. On shaft 10 are provided a plurality of crushing teeth or projections 11, disposed in similar manner to the teeth 8 on the main shaft. These teeth cooperate with a second concave, similar to the first, and with a similar crushing 50 effect. Their spiral dispositions on their respective shafts act to gradually feed the crushed grain longitudinally toward the separating partition between the hoppers. At 55 a point adjacent the partition, the shaft is provided with a hub 12 having spirally inclined vanes or feeding plates 13 adapted to push or feed the crushed grain longitudinally toward the partition. At the point where the shaft 8 passes through partition 60 or wall 4 there is an opening or passage 14 of considerable size substantially concentric with main shaft 8. Thus, the crushed grain, fed forward by the vanes 13 will be delivered through the opening 14 and into the hopper 3. That portion of shaft 8 which

extends through hopper 3 is provided from end to end with a screw conveyor blade or vane 15 which works in the usual concave bottom of that hopper. It operates to feed the material in the hopper lengthwise from 70 the separating partition into the space between the grinding discs α at the opposite end, by which discs it is ground and delivered in finished state, as will be readily understood. From these discs, after being 75 thoroughly ground, the mixture discharges through an opening or spout through the lower wall of the housing or casing of the grinding discs α . This screw conveyor, working in the concave, while conveying the material, also very thoroughly mixes it, receiving the crushed grain through the opening 14 and simultaneously receiving the chopped fodder through or from the fodder 80 chopping knives 7. Consequently, as long as the knives 7 keep up a supply of chopped fodder and the crushing rolls keep up a supply of crushed grain, the mixture delivered by the conveyor 15 will be regular and uniform 85 throughout. It is obvious that there can be no tendency of one constituent (the grain, for instance) to pass through the other, and be crushed and fed forward separately. In this construction, the fodder is 90 chopped separately and in a distinct hopper and the grain is crushed separately and in a distinct hopper, the two hoppers, however, adjoining and communicating and the two operations going on simultaneously. Thus, 95 the crushed grain and chopped fodder are prepared separately. They are then brought together and intimately mixed, the mixture, at the same time, being conveyed to the 100 grinding discs. This completely insures an 105 intimate and uniform mixture.

In mixed feeds of the character herein disclosed, it is often desired to vary the proportions of the constituents. To do this, the supply or feed of one or the other or both must be controllable. This can not be accomplished by regulating the delivery of the grain of the mixture as it passes into the final grinding discs. Attempts to regulate it in that way have resulted in choking or clogging the machine and putting it out of operation. Nor can it be accomplished by regulating the amount of one or the other of the constituents being fed into a single hopper because, during the operation, the grain will 110 pass through the fodder direct to the crushing rolls and be crushed, fed into the discs, ground and delivered before the fodder, resulting in two separate ground products— 115 grain and fodder, but no mixture. On the other hand, where the two constituents are chopped and crushed in separate but communicating hoppers and then mixed, it is obvious that regulation of the quantity of either constituent will affect the composition 120 of the resulting mixture. Thus, by 125 130

regulating the amount of crushed grain fed through the opening 14, the composition of the mixture or the relative proportions of grain to fodder may be accurately controlled 5 to maintain an even and uniform mixture of any desired proportions. For this purpose, a slide, shutter, or gate is provided. To the partition, 4, directly over the main shaft 8 and on the grain-hopper side, is 10 fixed a yoke-plate 16 of substantially U-shape in outline, the closed part of the plate lying above the shaft, while the two branches extend downwardly at either side and partly about the shaft, lying close to the surface of the shaft so that there is practically 15 no space between the shaft and this yoke. At a point near the top of the U-yoke is a guide pin 17. Pin 17 plays freely in an arcuate slot 18 in the substantially semi-circular 20 slide plate 19 which is adapted to travel freely over the face of the yoke. Several guide fingers, lugs, pins, or the like 20 extending from the yoke engage the edges of the slide plate and insure its travelling in 25 a path concentric to the longitudinal axis of shaft 8. The slot 18 is of such length and the pin 17 is so placed, that the slide plate will just fully close the gap or opening between the branches of the U-yoke when the 30 plate 19 is in one extreme position, while leaving it fully open when in the other extreme position, with all variations in degree of the opening, between those extremes. The head 21 of the guide pin 17 acts to retain the 35 guide plate superposed on the U-yoke, of course. From the outer edge of the slide plate, and a short distance from one end projects an ear 22 to which is pivotally connected one end of a pull rod 23, by which the 40 plate may be actuated. This rod is extended through the front side wall 24 of the grain hopper and provided with a handle whereby it may be operated. Preferably, one edge of this pull rod is notched to catch on the edge 45 of the wall 24 where it passes through the same, to provide means for securing the slide 19 in any desired adjustment. Various other arrangements might be used to attain the same result. Thus, when it is desired 50 to increase the grain content of the mixture, it is only necessary to pull the rod out, thereby pulling or sliding plate 19 upwardly along pin 17 over the face of the yoke 16 and increasing the space between the ends of the U. To decrease the grain content the 55 reverse movement is made. This, of course, is only one of the many forms of slide plates or other controlling means which may be very easily applied here, and is intended merely as an illustration of one form which 60 may be so used.

A machine constructed in accordance with this invention really combined, in a single compact combination, three machines each 65 performing its own particular function and

each cooperating with the others to accomplish a single result not obtainable except by such a combination. On the other hand, it is obvious that, if desired, the crushing mill may be used as a crushing mill, and the 70 fodder cutter simply cut out of operation. It is only necessary to slip the belt from the pulley of shaft 6. It is clear, of course, that the machine may also be used simply as a fodder chopper. 75

The feed rolls for drawing the fodder from the chute to the knives for chopping or cutting, the adjustability of the upper one, and the chain and sprocket drive for them, as well as the fodder chute itself and its 80 delivery to the hood 5, are all substantially the same as in the prior Patent 1,117,345, previously referred to.

A counter shaft 28, driven by gearing from the main shaft 8 drives the feed roll mechanism, the main shaft 8 being driven from any suitable source of power by the pulley fixed thereto. 85

Having thus described my invention, what I claim and desire to protect by Letters Patent is:—

1. A feed mill comprising two communicating hoppers in longitudinal alignment one adapted to receive grain and the other adapted to receive forage, means for cutting forage into the forage receiving hopper, grain crushing means within the grain hopper, means for feeding the grain from the grain hopper into the forage hopper, and means for regulating the feed of grain from 95 said grain hopper into said forage hopper. 100

2. A feed mill, comprising two hoppers one adapted in longitudinal alignment to receive grain and the other adapted to receive forage, a communicating opening being provided between the two through which crushed grain may be fed from the grain hopper to the forage hopper, means for cutting forage into said forage hopper, means for crushing grain in said grain hopper, means for feeding the crushed grain from said grain hopper into said forage hopper, and means for regulating the size of said 110 communicating opening to regulate the feed of crushed grain. 115

3. A feed mill comprising two hoppers in longitudinal alignment one adapted to receive grain and the other adapted to receive forage, a communicating opening being provided between the two through which crushed grain may be fed from the grain hopper, means for cutting forage into said forage hopper, means for crushing grain in said grain hopper, means for feeding the crushed grain from said grain hopper into said forage hopper, a slide plate adapted to regulate the size of the communicating opening, and means for actuating said slide plate. 120

4. A feed mill comprising two adjoining communicating hoppers one adapted to re- 125

- ceive grain and the other adapted to receive forage, a shaft extending continuously through both of said hoppers, said hoppers having a dividing wall with an opening considerably greater in diameter than the diameter of said shaft at the point where the shaft passes therethrough, a yoke plate extending about said shaft and closing the upper side of said opening, and a slide plate 5 cooperating therewith and adapted to regulate the size of the remaining portion of said communicating opening.
5. A feed mill comprising two adjoining communicating hoppers one adapted to receive grain and the other adapted to receive forage, a shaft extending continuously through both said hoppers, said hoppers having a dividing wall with an opening of considerably greater diameter than the diameter 10 of said shaft at the point where said shaft passes therethrough, a yoke plate extending about said shaft and closing the upper and side portions of said opening, a slide plate 15 cooperating therewith and adapted to regulate the size of the remaining portion of said communicating opening, and means for actuating said plate.
6. A feed mill comprising two adjoining communicating hoppers one adapted to receive grain and the other adapted to receive forage, a shaft extending continuously through both hoppers, said hoppers having a dividing wall with an opening of considerably greater diameter than the diameter 20 of the shaft at the point where said shaft passes therethrough, a yoke plate extending about said shaft and closing the upper and side portions of said opening, a slide plate 25 cooperating therewith and adapted to regulate the size of the remaining portion of said communicating opening, means for actuating said slide, and means for guiding said slide as it is operated.
7. A feed mill comprising two adjoining communicating hoppers one adapted to receive grain and the other adapted to receive forage, a shaft extending continuously through both hoppers, said hoppers having a dividing wall with an opening of considerably greater diameter than the diameter 30 of the shaft at the point where said shaft passes through said wall, a yoke plate extending about said shaft and closing the upper and side portions of said opening, a slide plate 35 cooperating therewith and adapted to regulate the size of the remaining portion of said communicating opening, means for actuating said slide, means for guiding said slide as it is operated, and means for 40 limiting the sliding movement of said slide.
8. A feed mill comprising two communicating hoppers, in longitudinal alignment, one adapted to receive grain and the other adapted to receive forage, a shaft extending continuously through both of said hoppers,
- grain crushing means carried by said shaft within said grain hopper, conveying and mixing means carried by said shaft within said forage hopper, and conveying means carried by said shaft between said crushing means and said first mentioned conveying means and adapted to feed the crushed grain from the grain hopper to the forage hopper.
9. A feed mill comprising two adjoining communicating hoppers, one adapted to receive grain and the other adapted to receive forage, a grinding mechanism, a shaft extending continuously through both of said hoppers, driving connections between said shaft and said grinding mechanism, grain crushing means carried by said shaft within said grain receiving hopper, and conveying and mixing means carried by said shaft and adapted to feed material from said hoppers into the aforesaid grinding mechanism.
10. A feed mill comprising two adjoining communicating hoppers, one adapted to receive grain and the other adapted to receive forage, a grinding mechanism, a shaft extending continuously through both of said hoppers, driving connections between said shaft and said grinding mechanism, grain crushing means carried by said shaft within said grain receiving hopper, conveying and mixing means carried by said shaft and adapted to feed material from said hoppers into the aforesaid grinding mechanism, and conveying means carried by said shaft between said crushing means and the aforesaid conveying means and adapted to feed the crushed grain from the grain hopper into the forage hopper.
11. A feed mill comprising two communicating hoppers in longitudinal alignment, one adapted to receive grain and the other adapted to receive forage, means for cutting forage into the forage hopper, a grinding mechanism, a shaft extending continuously through both of said hoppers, driving connections between said shaft and said grinding mechanism, grain crushing means carried by said shaft within said grain receiving hopper, mixing and conveying mechanism carried by said shaft within said forage hopper and adapted to simultaneously mix and feed forward to the grinding mechanism the crushed grain and chopped forage, and conveying means carried by said shaft between the aforesaid grain crushing means and the aforesaid mixing and conveying means and adapted to feed the crushed grain from the grain hopper into the forage hopper.
12. A feed mill comprising two adjoining communicating hoppers in longitudinal alignment, one adapted to receive grain and the other adapted to receive forage, means for cutting forage into the forage hopper, a grinding mechanism, a shaft extending continuously through both of said hoppers,

continuously through both of said hoppers, driving connections between said shaft and said grinding mechanism, means for driving said forage cutter from said shaft, grain crushing means carried by said shaft within said grain receiving hopper, mixing and conveying mechanism carried by said shaft within said forage hopper and adapted to simultaneously mix and feed forward to the grinding mechanism the crushed grain and chopped forage, and conveying means between the aforesaid grain crushing means and the aforesaid mixing and conveying means and adapted to feed the crushed grain from the grain hopper into the forage hopper.

13. A feed mill comprising a set of grind-

ing discs, a forage hopper adjoining and communicating with said discs, means for cutting forage into said forage hopper, a grain hopper adjoining said forage hopper, in alinement with said forage hopper and said discs and communicating with said forage hopper; grain crushing means within said grain hopper, means for feeding crushed grain from said grain hopper into the forage within said forage hopper, and means for simultaneously mixing the crushed grain and forage and feeding the mixture into said grinding discs.

Signed at Lancaster, Pennsylvania, this 30th day of June, 1922.

ABRAHAM M. DELLINGER.
